UNITED STATES PATENT OFFICE.

BENJAMIN F. ELLSWORTH, OF BROOKLYN, NEW YORK.

FINGER GUIDE FOR TYPEWRITERS.

Application filed January 17, 1925. Serial No. 3,208.

To all whom it may concern:

Be it known that I, BENJAMIN F. ELLSWORTH, a citizen of the United States, and a resident of Brooklyn, in the county of 5 Kings and State of New York, have invented a new and Improved Finger Guide for Type-writers and Other Keyboard Machines, of which the following is a specification.

This invention relates to keyboard finger 10 guides for type writing and other manually operated keyboard machines.

An object of the invention is to provide a simple and inexpensive finger guide which can be immediately applied to the keys without 15 screws, clamps, or other fastening means. Another object of the invention is to provide a device that will enable a learner to master easily the manipulation of a type-writer or the like by the so-called "touch 20 system".

The invention consists in providing a finger guide in the form of a plate of sheet metal or other suitable material adapted to be inserted between the keys operated by 25 the right hand and the keys operated by the left hand, the upper edge of which plate following the downward slope of the key grouping, and the plate having feet or other supporting means which rest preferably on the 30 table under the keyboard so that the guide is self-sustaining.

In order that my invention may be fully understood, there will now be described by way of example and with reference to the 35 accompanying drawings, a preferred construction of the finger guide in accordance with said invention.

In these figures:

Fig. 1 is a plan view of the finger guide 40 in position among the keys of a typewriter.

Fig. 2 is a perspective view of the finger guide.

Figure 3 is a view of the guide when flat, before bending to the form shown in Figs. 45 1 and 2.

The finger guide consists of a plate 1 of rigid sheet material, preferably metal, of such thickness as will enable the guide to extend downwards between the keys 2 and 50 key-levers 3 of a typewriter or other keyboard machine without interfering with the free manipulation of the keys. The plate is bent to follow the configuration of the right and left hand key groups A, B between 55 which it is inserted, this configuration being

clearly shown in Fig. 1. The upper edge 4 of the guide follows the downward slope of the key-board, so that this edge 4 is at a uniform and convenient distance, say about one-eighth of an inch, above the keys 60 2 for the purpose of guiding the fingers and preventing the fingers of either hand from straying into positions over the group assigned to the other hand. The lower portion of the guide is shown cut away to provide 65 three feet 5, the bottom edges 6 of which simply rest on the table or other surface 7 on which the machine is supported. The guide is thus entirely self-supporting and requires no screws, clamps, or fasteners 70 of any kind to support it in the machine when in use. Vertical support of the guide is provided entirely by the feet 5 while the guide is steadied or supported laterally by the keys and key levers between which it 75 passes.

In the illustrated example the vertical forward edge 8 of the guide has two notches or shoulders 9 and 10, as shown in Fig. 3, the upper and smaller shoulder 9 being intended 80 to engage the lower edge of the cover plate of the machine, and the lower and larger shoulder 10 being intended to pass over a cross-rod of the machine structure. It will be understood that the form of the 85 vertical forward edge of the guide may be varied as required to make the guide fit snugly and conveniently in whichever type of machine wherein it is to be used, but without in any way interfering with the 90 proper manipulation of the keys.

The finger guide of my invention is of great simplicity, is inexpensive to manufacture, can be quickly placed in position for use, and quickly removed when not required.

My finger guide is intended chiefly for use in the training of typists by the so-called "touch system" and when used on a standard typewriter keyboard the guide is preferably so located that the keys "5", "T", "G", "V", lie immediately to the left, and the keys "6", "Y", "H", "B", immediately to the right, of the guide, this being the standard line of division between the right and left hand key groups.

It will be seen that the objects of my invention as hereinbefore stated have been achieved.

The invention as hereinbefore set forth 110

is embodied in a particular form of construction, but may be variously embodied within the scope of the claims hereinafter made.

I claim:

- 5 1. A finger guide for keyboard machines consisting of a single piece of rigid sheet material adapted to be inserted between the keys and key levers operated by the right hand and the keys and key levers operated by the left hand, the upper edge of the guide being shaped to follow the downward slope of the keyboard at a suitable level above the keys, and the lower edge of the guide providing the sole vertical support for same when in use, by resting on any convenient stationary surface below the keyboard.
- 10 2. A finger guide for keyboard machines consisting of a single piece of rigid sheet material adapted to separate the keys into two groups for manipulation by the respective hands of the operator, said guide being steadied laterally by the several keys and their levers between which it freely
- 15
- 20

passes, and having feet constituting its sole vertical support when resting on any convenient stationary surface below the keyboard.

25 3. A finger guide for keyboard machines consisting of a plate of rigid sheet material bent into a configuration adapting it to separate the keys into two groups for manipulation by the respective hands of the operator, the upper portion of said plate extending slightly above the keys and the lower portion of said plate being formed with supporting feet for the guide when in use and adapted to rest on any convenient stationary surface below the keyboard.

30 4. A finger guide for keyboard machines having an upper portion forming the guide proper and adapted to stand between the keys to separate same into groups, and a lower sustaining portion extending downwards between the key levers of the machine to the surface whereon the machine rests.

35 BENJAMIN F. ELLSWORTH.
